ATTORNEYS.

UNITED STATES PATENT OFFICE.

THOMAS A. RYAN, OF YONKERS, NEW YORK.

FIREARM.

Application filed August 6, 1919. Serial No. 315,701.

To all whom it may concern:

Be it known that I, THOMAS A. RYAN, a citizen of the United States, residing in the city of Yonkers, county of Westchester, in 5 the State of New York, have invented new and useful Improvements in Firearms, of which the following, with the drawings, is a description.

My invention relates to improvements in 10 firearms of the magazine type, whereby, with each operation of the arm, simultaneously, the discharged shell from the barrel, and a loaded shell from a tubular magazine set under and parallel with the barrel, are 15 driven into the chambers aligned with the barrel and the magazine of a two chambered carrier, and the discharged shell of the previous shot is driven from the carrier chamber and the arm through the ejecting chamber, 20 the port of which is opened and closed by a shutter connected to the breech-bolt, the shutter carrying and connecting the mechanism to rotate the carrier until the positions of the chambers are reversed, carrying a 25 loaded shell from the magazine which is driven from the carrier chamber into the barrel by the breech-bolt, and carrying the discharged shell from the barrel, which is driven from the carrier chamber and the 30 arm, by the loaded shell as it enters the carrier chamber from the magazine, the carrier rotating between the backward and forward stroke of the breech-bolt on a cocking rod connecting the magazine and the 35 breech bolt, the rod cocking the arm, the arm operated by the discharge, or by a hand-grip on the magazine.

The invention should be readily understood from this description and specifications 40 and the accompanying drawings in which each part is shown separately and the parts assembled showing the operation of the arm.

Fig. 1 is a longitudinal view partly in 45 cross section showing the several operating mechanisms in the position they occupy immediately after firing and the instant the carrier makes its half turn. Fig. 2 is a similar view showing in cross section the parts 50 not shown in Figure 1. In this view the arm is shown cocked ready to fire. Fig. 3 is a similar view to Figure 1 showing the tumbler replaced by a hammer, the firing pin carried in the breech-bolt and the shell grip in the 55 breech-bolt head. Fig. 4 is a longitudinal view partly in cross-section showing the po-

sition of the mechanism the instant the hammer strikes the firing pin the shell being held against recoil by the sear locking the hammer firing pin and the breech-bolt. 60

Fig. 5 is a cross section of the barrel through the barrel lug 3².

Fig. 5^a is a fragmentary side elevation thereof, parts being in section.

Fig. 6 is a detached view of the magazine 65 tube.

Fig. 7 is a rear view of the carrier.

Fig. 8 is a side view of the front of the frame, cut away to more clearly show the rotating mechanism for the carrier, which 70 is shown in the middle of a half revolution.

Fig. 9 is a sectional plan, showing the mechanism for rotating the carrier.

Fig. 9^a is a side elevation thereof.

Fig. 10 is a side elevation of the breech 75 bolt.

Fig. 10^a is a cross section thereof.

The arm is assembled and operates as follows: The breech-end of the barrel 3 and the lug 3² fit the frame hole 2¹ and the recess 2² 80 and are held locked, by the rod 12 in the barrel lug hole 3³. An L shape breech-bolt 10 has a center hole, in which slides the reduced portion of a firing pin 11, the diameter of the large portion of the firing pin 11 and 85 the bolt 10 being equal, and a sliding fit for the frame hole 34, compressing the spring 32 as it moves back the flat portion 10⁷ sliding in a channel connecting the hole 34 with the hole 35 in which slides the round 90 part 10² compressing the bolt spring 33. Projecting outward at right angles from opposite sides of part 10², are arms 10⁵ the 95 ends of which are adapted to slidably engage the upper slots 18³ of the levers 18. The cocking rod 12, connects with the center 100 of 10², and projects backward as shown at 10⁴. From the under side of 10² a lug projects downward holding the shells in the carrier and the magazine when the position of 105 the arm is not level. The levers 18 are movably pinned through the center hole 18² to the side walls of the ejecting chamber 36 and the lower slots 18³ movably pinned to the lugs 21¹ of the shutter 21. The lever 20

is movably pinned near its pointed end to the inner face of the shutter 21, and carries 110 slidably in the hole 19³ and the keyway 19⁴ an angle member 19, the upright leg of which is encased in a spiral spring 19¹, and having along its side a longitudinal key 19². The shutter 21 slides in channels cut in each

side of the port of the ejecting chamber 36 opening and closing the port of the ejecting chamber. A flat spring 22 one end of which is secured to the frame, projects backward diagonally, having a lateral alignment with the lever 20, and is engaged by the lever 20 as the shutter 21 moves back. It will be noted, that as the shutter 21 moves forward, the end of the spring slides along the lever 20, but before the end of the spring 22 has passed the pivot point where the lever 20 is pinned to the shutter 21, the end of the angle member 19 has entered the hole 9³ or 9⁴ of the carrier 9, this holds the lever 20 against movement, thus the lever 20 forces back the spring 22 as the shutter completes its forward stroke. When the shutter 21 has completed its forward stroke the projecting end of the angle member 19, is length deep in the hole 9³ or 9⁴ of the carrier 9, and the flat spring 22 is forced back until it is straight. It will be further noted, that at this point the rotating mechanism holds the carrier 9 in a cocked position, ready to be sprung, the instant the breech-bolt 10 moving backward out of the upper carrier chamber clears the carrier, the stored energy in the spring 22 forcing the lever 20 connected to the carrier 9 by the angle member 19 across the face of the shutter 21, the shutter 21 being slightly concaved in the path of the lever 20 to facilitate the turning of the carrier 9, thus overcoming the tendency of the carrier to hold on a dead center, as the lever 20 carrying the angle member 19 turns the carrier 9 until the position of the carrier chambers have been reversed, the loaded shell being now in the upper and the discharged shell in the lower chamber of the carrier 9. As the carrier 9 completes its half turn the breech-bolt 10 moves forward through the upper carrier chamber forces the loaded shell from the carrier chamber into the barrel, and the discharged shell in the lower carrier chamber is forced from the carrier and the arm through the ejecting chamber 36, by a loaded shell fed from the magazine into the carrier chamber as the breech-bolt makes its backward stroke.

The levers impart a movement to the shutter 21 in a direction reverse to and simultaneous with the movement of the breech-bolt 10, the shutter closing the ejecting chamber port, as it moves back, the projecting end of the angle member 19, withdrawing said member from the carrier hole 9³ or 9⁴. The lever 20 is engaged by the end of the spring 22, forcing the lever 20 back after it passes the pivot and setting the projecting end of the angle member 19 in alignment with the hole 9³ or 9⁴ in the carrier 9 for the next shot.

The shell magazine, set under and parallel to the barrel, is composed of two tubes 6 and 7 and a plunger 23, also a hand-grip 8,

the plunger 23 sliding endwise in the inner tube 6, and has set longitudinally, movingly pivoted at one end in a slot a lever 23¹ having a pointed end held outward by a spring set under the lever, a bridge in the upper part of the slot engaging the end of the lever holding same in the slot, the lever having pinned at each side flat springs, the projecting ends of the springs having lateral alignment with the V shape slots 6³ cut in the edge of the longitudinal slot 6¹ of the tube 6, in which the lever slides, the pointed end of the lever engaging the longitudinal spaced teeth cut in the inner face of the outer tube 7, aligned with the slot B of the inner tube 6, the spacing of the teeth corresponding to the length of the shell or cartridge to be used in the arm. When the outer tube 7 is moved backward the plunger 23 moves with it, and is held in its advanced position by the projecting flat springs on either side of the plunger lever 23¹, engaging the V shape slots cut in the edges of the slot 6¹ of the inner tube 6, as the outer tube 7 moves forward, the plunger lever engaging an advanced tooth in the outer tube 7, setting the magazine to eject the next shell. The magazine is secured to the frame by setting the cross slot 6² of the inner tube 6 in engagement with the projecting pin 2⁴ in the frame hole 2³, and connecting the nipple 13 turning in hole 7² of the lug 7³ of the tube 7 with the cocking rod 12. This connects the magazine with the breech-bolt 10 and the shutter 21 carrying the rotating mechanism, also with the firing mechanism. The arm is operated automatically by the force of a discharged shell, recoiling carrying the breech-bolt back compressing a spring set in the path of the breech-bolt and a spring compressed by a firing-pin carried in the breech-bolt, a cocking rod setting the firing mechanism, and cocking the gun, the stored energy in the springs 32 and 33 set in the holes 34 and 35 the breech-bolt spring 33 setting the breech-bolt loading a shell from the magazine, by the rotating mechanism, and closing the port of the ejecting chamber, or the bolt is operated by a to and fro movement of the handle 8. The changes in the construction of the gun with a hammer is shown in Figure 3. The firing-pin spring 32, the tumbler 15 and the locking lever are not used, a trigger 29 and a hammer 28, having a spring, hole is cut through the rear of frame the enlarged end of the firing pin is made longer and has no notch, the smaller end having a pointed cap screwed on its end holding the firingpin in the breech-bolt. In Figure 4 the arm is shown without the breech-bolt spring 33, having a hammer 42, with a tumbler 41 movingly pivoted in the recess 42¹, the edges of which are cutout as 42². The hammer is held cocked and locked

by a sear 16, the head of the sear 16 set by the sear spring in engagement with the cutouts 42² when the hammer flies down firing the arm, locking the hammer and the 5 breech block against the discharged shell in the barrel. As the hand-grip is moved back the cocking-rod engages the tumbler 41 the L shape end forcing the sear 16 from the cutouts 42² cocking the hammer, 10 the sear 16 moving back under the point 42³. When the trigger 39 is pulled it forces the sear 16 into the hole 43 firing the gun. The shell extractor in the head of the breech-bolt is formed by the two diametral L shape 15 ends 29¹ and 29² engaging the rims or grooves of a shell, the lateral projections sliding in the longitudinal keyways 9⁷, 9⁸, 9⁹, and 9¹⁰ cut in the carrier chambers the 20 end projections standing in the circular keyways 9⁵ and 9⁶ as the carrier turns, and fitted recesses cut in the breech end of the barrel.

It will be noted that the arm can be operated automatically, semi-automatic, or by 25 the hand-grip on the magazine, and is adapted for a hammerless or hammer fire. In Fig. 1 and Fig. 2 the automatic is shown, the explosive force of the discharged shell recoils the breech-bolt back compressing 30 the breech-bolt spring 33, and cocking the arm, the stored energy in the spring completing the operation. When a breech-bolt spring 33 is not used, the explosive force 35 of the discharged shell forces the breech-bolt back and cocks the arm and the operation of the arm is completed by moving forward the hand-grip, or the entire operation of the arm, performed by a to and fro movement of the hand-grip. When the 40 arm is automatic in operation by using the breech-bolt spring, it does not prevent the use of the hand-grip, the arm being locked or the hammer held while the mechanism is operated by the hand-grip to load the magazine or adjust the shells.

The magazine is loaded, by turning the inner tube 6, which throws the lever 23¹ of the plunger 23 out of engagement with teeth cut in the tube 7, and the flat springs on 50 the sides of the lever clear of the V shaped slots 6³ cut in the edges of the slot 6¹ of the tube 6, which permits the plunger 23 to slide back as the shells are placed in the tube 6 through the ejecting chamber 36, or 55 the nipple 13 can be unscrewed from the rod 12 and the magazine removed from the frame while the shells are placed in the tube 6.

What I claim as my invention is:—

60 1. In a firearm, the combination with a barrel, a firing mechanism cooperating therewith comprising a movable breech-bolt adapted to be driven back by the recoil of a shell upon discharge, actuating springs for said breech bolt and firing pin and a cocking

rod connected to the breech-bolt, a shell magazine, and means to convey a loaded shell from said magazine to said barrel and a discharged shell from said barrel and arm comprising a two chambered carrier, an 70 ejecting chamber having an ejecting opening, a shutter for normally closing said opening, connections between said bolt and shutter for operating the shutter and mechanism operated by the movements of 75 said bolt for rotating said carrier through half a revolution at each shot, and additional means for manually retracting the bolt to load and cock the arm.

2. In a firearm, the combination with 80 a barrel, a firing mechanism, a two chambered carrier, rotated on a cocking-rod, means to change the position of the carrier chambers by a half rotation, said rod having a reciprocating movement through the 85 center of the carrier, a movable breech-bolt and a shell magazine, said rod connecting the bolt and magazine and adapted to cock the arm as set forth.

3. In a firearm the combination with a 90 barrel, a firing mechanism, a movable breech-bolt, a tubular magazine set under and parallel with the barrel, having an operating hand grip, a reciprocating tube secured to said hand-grip, said tube having spaced 95 teeth longitudinally, a tube adapted to hold shells and having a longitudinal slot registered with the spaced teeth of the reciprocating tube, a plunger sliding in said shell tube, a lever pivoted in said plunger, and having flat projecting springs pinned to each side, having an operating spring and stops for said lever, said plunger adapted to expel shells from said shell tube, means 100 to engage said plunger lever with the spaced teeth of the reciprocating tube, means to advance said plunger step by step by the recoil of a discharged shell, or by a to and fro movement of the said hand grip, having 105 V shaped cuts spaced along each edge of the longitudinal slot of shell tube, means to engage the flat springs of said plunger lever, with said V shaped cuts successively, whereby the plunger is held as the reciprocating tube is moved back until the plunger lever engages an advanced tooth of the reciprocating tube, by the stored energy in a spring compressed by the recoil of an exploded shell against said breech-bolt, or by 110 the hand grip, and having means to release 115 the plunger and load the magazine, as set forth.

4. In a firearm, the combination with a 120 barrel, a firing mechanism, a movable breech-bolt having a round projecting portion in which slides a firing-pin, said firing-pin having one dimension equal to the round portion of the breech-bolt, said round portion having projecting outward diametrically opposed L shaped shell extractors, having 125 130

means to hold shells in a magazine, and having means to drive a loaded shell into a barrel, and extract the discharge shell, means to connect said breech-bolt to a shell magazine, 5 whereby a loaded shell is conveyed from the magazine and driven into the barrel with each to and fro movement of said breech-bolt, means to connect said breech-bolt to a shutter opening and closing an ejecting port 10 with each to and fro movement of said breech-bolt, means to connect said breech-bolt to a rotating mechanism whereby each to and fro movement of said breech-bolt connects said rotating mechanism with a 15 two chambered carrier and an operating spring, means for disconnecting said rotating mechanism from said carrier and spring after the carrier has rotated, a cocking-rod connecting said breech-bolt to a magazine, 20 and adapted to cock the arm, as set forth.

5. In a firearm, the combination with a barrel, a firing mechanism, a tubular shell magazine, a cocking-rod connecting said magazine to a movable breech-bolt having 25 projecting diametrically opposed L shaped extractors, standing in circular recesses cut in a two chambered carrier, whereby shells are released and engaged by said extractors, means to connect said breech-bolt to a 30 reciprocating shutter opening and closing an ejecting port, said shutter having pivoted to its inner face a lever carrying an angle member slidale in its end, means to alternately engage holes in a carrier, and having 35 means whereby said lever compresses a flat projecting spring the stored energy in said spring rotating a two chambered carrier to

reverse the chambers with each rotation, as set forth.

6. In a firearm, the combination with a 40 barrel, a shell magazine, a movable breech-bolt, a two chambered carrier, a cocking-rod connecting the breech-bolt and magazine, the carrier rotating on the cocking-rod, a 45 firingpin carried slidably in said breech-bolt, a shutter and a rotating mechanism connected to said breech-bolt, a hammer having a recess in which is pivoted a tumbler, adjacent to a cross recess engaged by a sear having a large head and encased in an operating spring reciprocating in a hole in the frame, said sear engaging the cross recess as the hammer flies down, thereby locking the breech-bolt against the exploding shell, means to unlock hammer and breech-bolt, withdraw the discharge shell from the 50 barrel and breech-bolt, and engage a loaded shell in shell extractors on said breech-bolt and drive same into barrel, means to open and close an ejecting port, set said rotating 55 mechanism to rotate said carrier, expel a discharged shell from the arm, and cock the gun, the parts combined and constructed in such manner to operate as described by a to and fro movement of a hand-grip secured 60 to the magazine, as shown and described.

In testimony whereof I have signed my name to this specification in the presence of two subscribing witnesses.
